[57] CLAIM

The ornamental design for a handbag, as shown and described.

DESCRIPTION

FIG. 1 is a front perspective view of a handbag showing my new design with the closure flap partially raised; FIG. 2 is a left end elevational view thereof with the closure flap closed, a portion of the carrying strap being broken away and omitted for convenience of illustration; and

FIG. 3 is a bottom rear perspective view with the closure flap and carrying strap partially raised.
